(57) **CLAIM**

The ornamental design for an atomizer as shown and described.

DESCRIPTION

FIG. 1 is a front right perspective view of an atomizer showing our new design according to one embodiment; FIG. 2 is a front view of the design shown in FIG. 1; FIG. 3 is a rear view of the design shown in FIG. 1; FIG. 4 is a right side view of the design shown in FIG. 1; FIG. 5 is a left side view of the design shown in FIG. 1; FIG. 6 is a top view of the design shown in FIG. 1; FIG. 7 is a bottom view of the design shown in FIG. 1; FIG. 8 is an exploded view of the design shown in FIG. 1; FIG. 9 is a front right perspective view of an atomizer showing our new design according to another embodiment; FIG. 10 is a front view of the design shown in FIG. 9; FIG. 11 is a rear view of the design shown in FIG. 9; FIG. 12 is a right side view of the design shown in FIG. 9; FIG. 13 is a left side view of the design shown in FIG. 9; FIG. 14 is a top view of the design shown in FIG. 9; FIG. 15 is a bottom view of the design shown in FIG. 9; FIG. 16 is a front right perspective view of an atomizer showing our new design according to another embodiment; FIG. 17 is a front view of the design shown in FIG. 16; FIG. 18 is a rear view of the design shown in FIG. 16; FIG. 19 is a right side view of the design shown in FIG. 16; FIG. 20 is a left side view of the design shown in FIG. 16; FIG. 21 is a top view of the design shown in FIG. 16; and, FIG. 22 is a bottom view of the design shown in FIG. 16. The figures include broken and solid lines. The broken lines shown in the figures are included for the purpose of illustrating portions of the atomizer and form no part of the claimed design.
